UNITED STATES PATENT OFFICE.

JOSEPH FORSHEIM, OF NEW YORK, N. Y.

DESIGN FOR A SUSPENDER-BUCKLE.

SPECIFICATION forming part of Design No. 25,093, dated January 28, 1896.

Application filed September 12, 1895. Serial No. 562,336. Term of patent 7 years.

To all whom it may concern:

Be it known that I, JOSEPH FORSHEIM, of the city and county of New York, in the State of New York, have invented and produced a new and original Design for Suspender-Buckles, of which the following is a specification, reference being had to the accompanying drawings, forming a part thereof.

The leading features of my design consist in a suspender-buckle presenting a series of parallel bars spaced from a field into which they merge at their ends, the spaces between the successive two bars being of unequal widths.

In the accompanying drawings, Figure 1 represents a plan view, and Fig. 2 a trans-

verse sectional view through the line x x of Fig. 1.

The parallel bars are denoted by A A' A². The field from which they are spaced and into which they merge at their ends is denoted by B, and the space a between the bars A and A' is wider than the space a' between the bars A' and A².

What I claim is—

The design for a suspender-buckle, as herein shown and described. 25

JOSEPH FORSHEIM.
